DRAWING IN FRAME

John G. Bentley and Robert A. Gibbs, Jr.,
Greensboro, N. C.

Application June 1, 1931. Serial No. 541,427

11 Claims. (Cl. 28—44)

This invention relates to a drawing in frame and has for one of its objects the provision of an entering frame in which unnecessary lifting of the warp roll is eliminated, in that means are provided for receiving the warp roll in a lowered position and preferably from a truck as disclosed in co-pending patent application, Serial Number 510,048, filed on the 20th day of January 1931, by John G. Bentley.

After the warp roll is received into the drawing in frame, means are provided for hoisting the warp roll to an elevated position and automatically stopping in proper position where the warp roll will rest while the threads are entered through the heddles in the harness frames and then thru the comb and then secured to a take-up roll which has means for holding the same in adjusted position. After the above entering operation has been completed, the hoisting apparatus can be started and the warp roll will be lowered to its original position and in which position the drop wires may be installed and when these drop wires are installed the warp and harness and combs and drop wires and take-up roll are all ready to be installed in a loom.

Heretofore, it has been the practice in the old types of drawing in frames to summon two or more men to hoist the warp roll to an elevated position by manual means and then to secure the same by a rope or on hooks and the like and then when the warp roll is to be lowered to its lowermost position for the placing of the drop wires, it is then necessary to require the services of two or three men to move the warp roll to the lowered position for the installation of the drop wires.

By means of the improved structure set forth in this application, it is possible for the operator of the drawing in frame, that is the one engaged in entering the warp into the heddles and the like, to operate this drawing in frame to raise the warp roll by any suitable means such as an electric motor and to lower the same to lowered position without the necessity of summoning additional aid for the raising and lowering operations.

Some of the objects of the invention having been stated, other objects will appear as the description proceeds when taken in connection with the accompanying drawings, in which—

Figure 1 is a front elevation of the drawing in frame;

Figure 2 is a side elevation of the drawing in frame, showing the parts in position for installing the drop wires;

Figure 3 is a view taken along the line 3—3 in Figure 1;

Figure 4 is a view taken along the line 4—4 in Figure 1;

Figure 5 is a side elevation of the drawing in frame with certain of the parts shown in different positions from that in Figure 2;

Figure 6 is a view taken along the line 6—6 in Figure 2;

Figure 7 is a plan view taken along the line 7—7 in Figure 6;

Figure 8 is a sectional view taken along the line 8—8 in Figure 7;

Figure 9 is a sectional view taken along the line 9—9 in Figure 1;

Figure 10 is a sectional view taken along the line 10—10 in Figure 9.

Referring more specifically to the drawings, the numerals 10 and 11 indicate the upright members of the frame, and these members 10 and 11 have therein the vertical slots 10a and 11a respectively. Members 136 and 120, which will be later described, pass thru and have slidable contact with slots 10a and 11a respectively. The lower ends of members 10 and 11 are secured to base members 12 and 13. These base members 12 and 13 are in turn secured together by another base member 14.

Members 10 and 11 at the upper end thereof are secured together by a cross member 15. Secured to member 15 are two upstanding members 16 and 17 which have a plate 18 spanning the distance between them, and fixedly secured to their upper ends. This forms a base for a reversible motor 19, said motor having pulley 20 with an endless belt 21 thereon passing over and around another pulley 22. Leading from the motor is a conduit 23 which leads to a reversing switch 24 which is fixedly secured by means of bolts 25 and 26 to member 10. Leading from this switch is another conduit 27 which leads to a source of power 29a,

and this switch has thereon an arm 28 to which is fastened a switch rod 29, said switch rod being slidably mounted in an outstanding lug 30 which is fixedly secured to the front face of member 10.

Fixedly secured on rod 29 is a lug 31 with handle portion 32, and near the lower end of rod 29 is fixedly mounted a lug 33 which has the outstanding portion 34. Around rod 29 and between members 30 and 33 is mounted a coil spring 35. Near the upper end of this rod is mounted a member similar to member 33, this member being designated by the reference character 37, with outstanding portion 38. The members 33 and 37 are adapted to be struck at times by certain of the

100
105
110

parts to stop the motor, the action of which will be later described.

On member 15 near one end thereof is fixedly mounted an upstanding member 40, having bearing portions 41 and 42, and at the upper end thereof has a U-shaped portion 43 which has in one leg thereof a bearing portion 44, and on the other leg thereof has a bearing portion 45. Mounted in bearing portions 44 and 45 is a shaft 10 46 which has thereon a worm 47, and the pulley 22 (see Fig. 4). Near the other end of member 15 is mounted an upstanding member 48 which has at its upper end a bearing portion 49. Mounted in the bearing portions 41, 42 and 49 is a shaft 50 15 which runs parallel to member 15, and mounted on this shaft 50 at one end thereof is a drum 51, and on the other end thereof is mounted a similar drum 52. Between these drums and in close proximity to bearing portion 42 is mounted a worm 20 gear 53, meshing with worm 47.

Fixedly secured on the upper surface of member 15 are the two backwardly projecting members 55 and 56 (see Figs. 1 and 2), these members being made of angle iron and having mounted at their 25 rear ends downwardly projecting U-shaped members 57 and 58 for receiving beam 215 when not in use. On the under surface of these members 55 and 56 are mounted wooden strips 60 and 61. Mounted in these strips 60 and 61 is a plurality 30 of hooks 62 which pierce holes 63 in strap members 64, there being a plurality of these holes 63 in each strap member 64 to allow for adjustment. At the lower end of strap members 64 are holes 65, there being a plurality of these holes 65 35 in each strap member to allow for adjustment. Piercing holes 65 are hooks 66 which have secured thereto cord members 67 which have secured at their lower ends threaded rods 68 which threadably engage a turn buckle 69. Removably mounted 40 in the lower end of turn buckle 69 are members 70 which are fixedly secured to harness frames 71, 72, 73 and 74.

On the underneath surface of members 55 and 56 and running longitudinally with member 15, 45 is a rod 75, and near each end of this rod are mounted the cord members 76 and 77. These members 76 and 77 have therein loops 78, 79, 80, 81, 82 and 83. These members 76 and 77 are secured at their lower ends to member 14 by means of hooks 85 and 86 passing through loops 50 87 and 88.

Mounted around drum 51 and fixedly secured thereto is a cable 90, and this cable 90 projects downwardly and into hollow upstanding member 11 and fastens to a dog 91 forming a part of a safety mechanism disposed in each upright 10 and 11 which is mounted in a slidable member 92 which is also on the interior of member 11. This dog 91 is mounted on a pin 93 which is mounted 55 in the sidewall portions 94 and 95 of member 92. This shaft 93 has a non-rotatable drive fit in the sidewall portions 94 and 95 and the ends thereof are peened to further fixedly secure this shaft 93. Dog member 91 has the lower end thereof serrated 60 as at 96, and at the upper end thereof has an outstanding lug 97 in which is mounted one end of a tension spring 98 which projects downwardly and is secured to a pin 99 mounted in sidewall portion 100 of member 92. Near the upper end of member 92, and mounted in the sidewall portions 65 94 and 95, is a shaft 101 which has a drive fit in the sidewall portions 94 and 95.

The ends of the shaft 101 are peened as at 102 and 103, and rotatably mounted on this shaft 101 are rollers 104 and 105. Portions of the side-

wall 100 are cut away as at 106 and 107 to allow these rollers 104 and 105 to have contact with the inside of member 11. A tongue portion 108 which is left when the openings 106 and 107 are cut in member 100 serve to space the rollers 104 and 105. Near the lower end of member 92 and similarly mounted are the rollers 110 and 111 on shaft 112 which project through sidewall portion 113 of member 92. 80

Slots 114 and 115 are cut to allow the rollers 110 and 111 to pass through sidewall 113 and have contact with the interior of member 11. In cutting these slots a portion 116 is left in sidewall 113 to serve as a spacer for the rollers 114 and 115. The above arrangement is present in 90 each upright 10 and 11 and forms a safety mechanism which prevents falling of the beam in case either of the cables breaks. 85

Mounted on the outside of sidewall portion 100 of member 92 is a forwardly projecting arm 120. 95 This arm 120 has the short portion 121 which has one end thereof notched to form the lugs 122 and 123. The other portion 126 of arm 120 has lugs 124 and 125 thereon and by passing a bolt 127 thru these lugs it is seen that a hinge joint 100 is formed between the portions 121 and 126. Mounted on the inside face of member 121 and projecting inwardly is a pin 128, the purpose of which will be presently described. At the forward end of member 126 and near the upper edge 105 thereof is a U-shaped bearing 130.

Passing around drum 52 and fixedly secured at one end thereof is a cable 135 and this cable projects downwardly and into the interior of member 10, and the other end thereof is fastened to 110 a member similar to member 92 in every detail except that it has the forwardly projecting arm 136 which has the inwardly projecting pin 137 and a U-shaped bearing 138 at the outer end thereof, and this member 136 is similar to member 115 120 except that it is not hinged as at 127.

Fixedly secured to the exterior of member 10 is a circular plate member 140 having an outstanding bearing bolt 141 on which is pivotally mounted a circular plate member 142. 120

Member 142 is secured in position by means of washer 143 and nut 144 and projecting from plate member 142 is an arm 145. Arm 145 is round in cross section and has an inwardly projecting portion 146 and a backwardly projecting portion 147 and an upwardly projecting portion 148, and in the upper end of this portion 148 is a U-shaped bearing 149. Pivotally mounted on the portion 145 as at 150 is a pawl 151, the purpose of which will be presently described. Member 142 has an outstanding boss 152, which boss has a circular cavity 153 in which is slidably mounted a pin 154 which is adapted to fit in cavity 155 in member 140 at certain times. This pin 154 has a smaller portion 156 which has 135 thereon at the outer end thereof a button 157 which button is adapted to be gripped by the fingers to pull pin 155 from engagement with portion 140. Mounted around portion 156 and in the cavity 153 is a compression spring 158 which normally forces pin 154 into cavity 155. Mounted on the exterior of member 11 is a plate member 160 which is similar in detail to plate member 140, and pivotally secured to member 160 is a plate member 161 which is identical to member 142, and projecting from member 161 is an inwardly and backwardly and upwardly projecting arm 162, this arm having at the top of the upwardly projecting end U-shaped bear- 140 145 150

ing 163, and this arm is similar in detail to arm 145 except that it does not have the pawl 151.

After the warp has been slashed and wound on the loom beam 175 it is then brought to this drawing in frame and may be brought on a truck or by any other suitable means. Beam 175 has a shaft 176 passing therethrough and extending from each end thereof, and the beam has drum portions 177 and 178 on the respective ends thereof. The portion 126 of member 120 is swung outwardly and one end of shaft 176 is placed in bearing 138 and then member 120 is swung back into position and the other end of shaft 176 is placed in bearing 130, the purpose of the swinging of member 120 is to make it possible to engage shaft 176, in bearing 138 without undue lifting. The ropes 180 and 181 are passed several times around the drum portions 177 and 178 respectively, and rope 180 is secured to pin 128 in member 120 by means of a loop in one end thereof. The other end of this rope has a loop 184 in which the hook portion of a weight supporting member 185 engages. This weight supporting member having thereon removable weights 186, 187 and 188, and rope 181 is secured at one end to pin 137 in member 136 by means of a loop 183, similar to loops for rope 180. The other end of rope 181 has loop 189 in which is mounted the hook portion of a weight supporting member 190 on which are mounted removable weights 191, 192 and 193. The beam is now in condition to be raised to the position shown in Figure 5 for entering the warp threads thru the harness.

The only weight necessary to be used for the following operation is the weight 193. As it is desired to move the beam upwardly, the operator grasps handle 32 of member 31 (see Fig. 1) and moves it upwardly. This throws the switch 24 and causes motor 19 to rotate clockwise in Fig. 1 and thus causing the drums 51 and 52 to move clockwise in Fig. 2 and wind the cables 90 and 135 therearound. This imparts upward movement to the member 92 and the arms 120 and 136 on which are mounted bearings 130 and 132 in which the end portions of the beam shaft 176 are mounted causing the beam to move upwardly. The beam moves upwardly until member 136 strikes portion 38 of member 37 on switch rod 29. This opens the circuit to the motor and stops the beam in the position shown in Figure 5. The beam is in position for the drawing in process to begin. Lease rod 200 is slipped thru loops 78 and 81. Similar rods 201 and 202 are passed thru the loops 79, 82, (Fig. 1) and also 80 and 83 respectively. The warp threads are then passed over rod 200 and to the left of rod 201 (Figure 5) and every alternate thread is passed to the left of and beneath rod 202, and the other half of the threads are passed to the right of rod 202. The threads are then passed through the heddles 71 to 74 and alternate threads are passed above rod 205 while the other threads are passed beneath rod 205. Then all of the threads are passed thru reed 213.

This lease rod 205 may be supported by any suitable means such as by tying it to the top of the harness frame with a cord 195. The warp is then passed thru the reed 206. This reed is supported by two brackets 207 which brackets have the upwardly extending portions 208, laterally extending portion 209, downwardly extending portion 210, the laterally extending portion 211, and the upwardly extending portion 212, the same being supported in the harness frames.

After passing thru the reed, the warp is then tied as at 213.

The arms 147 and 162 are now moved to the position shown in Figure 2, being held in position by means of pins 154 engaging cavity 155 in member 140 (See Fig. 8). A beam 215 has thereon a ratchet wheel 216, this beam having bearing portions 217 and 218, and this beam has fixedly secured thereon one edge of a piece of fabric 219, the other edge of this fabric having secured thereto the rod 220. The fabric 219 has notches 221 therein where it is secured to rod 220 to permit bunches of warp threads to be passed therethrough (Fig. 7). The bearing portions 217 and 218 of beam 215 are placed in bearings 149 and 163 on arms 145 and 162 respectively, taking a position as shown in Figure 2.

The rod 200 is then removed and the operator grasps portion 32 of member 31 and pulls it downwardly. This reverses and closes switch 24 causing the motor to rotate in a counter clockwise motion in Fig. 1 and causes the cables 90 and 135 to unwind from drums 51 and 52, thus moving member 92 and its associated parts downwardly until arm 136 strikes portion 34 of member 33, thus pulls switch rod 29 downwardly and opens switch 24, thus stopping the beam in the position shown in Figures 1 and 2.

The lease rods 201 and 202 are removed from loops 79, 82, 80, and 83 and are drawn to the position shown in Figure 2.

The reed is raised from the position shown in Figure 5 to that shown in Figure 2, and the lease rod 205a is inserted on the other side of the reed 206 and rod 205 is withdrawn from the position shown in Figure 5 and is discarded. The ends of the warp are now tied around rod 220 as at 225 (See Fig. 7). Tension is now applied to the warp by moving ratchet wheel 216 in a clockwise direction in Fig. 2, and the pawl 151 prevents this ratchet wheel from slipping backward or in a counter clockwise direction in Fig. 2 when tension is applied to the warp.

A plate member 225 having spaced holes therein to accommodate the rods 201 and 202 is applied over the ends of these rods. A similar plate member 221 is placed over the other end of these rods, and these plate members have notches in which are placed the ends of horizontally extending bars 222 and 223 (See Fig. 2). These bars 222 and 223 serve as a support for the drop wires 224 when they are placed over the warp. After all of the drop wires are placed over the warp as shown in Figure 2, the warp is untied from rod 220 and tied behind lease rod 205a as shown at 230 in Figure 7. After all of the warping is tied behind the rod 205a, the warp is in condition to be moved to the loom. The plate members 220 and 221 are removed from the ends of rods 201 and 202, the harness frames are detached from the straps 64, the ropes 180 and 181 are removed from the drum of the warp beam, and the warp beam is rotated in a counter clockwise motion in Fig. 2, thus drawing the lease rods 201, 202 and bars 222, 223, and the associated drop wires, the harness frames, the reed and the lease rod 205a therearound it, or as nearly so as possible. The beam is then taken from the drawing in frame to the loom.

When the warp is removed from rod 220 and secured to rod 205, the beam is placed in hooks 57 and 58 where it remains until the frame is again used, as shown in Figure 5.

In the drawings and specification there has been set forth a preferred embodiment of the in-

vention and although specific terms are employed they are used in a generic and descriptive sense only and not for purposes of limitation, the scope of the invention being set forth in the appended 5 claims.

1. In a drawing in frame, having a take-up roll, harness frames, means for receiving the warp roll, means for raising the warp roll, means for automatically stopping the raising means when 10 the warp roll has been raised to predetermined height, means for lowering the warp roll, and means for automatically stopping the lowering operation when the warp roll has reached a predetermined point in the lowering operation.
2. In a drawing in frame comprising a take-up roll, harness supporting means, lease rod supporting means, means for receiving a warp roll, means for raising the warp roll to a predetermined height in said frame, means for automatically 20 stopping the raising operation when the warp roll has reached a predetermined height and safety means for preventing the warp roll receiving means from moving downwardly when a portion of the raising means becomes broken.
3. In a drawing in frame, a framework, vertically disposed uprights in said framework, guideways in said vertically disposed supports, arms extending from said guideways, one of said arms having a pivot intermediate its ends, said arms 30 having bearing portions in the outer ends thereof for receiving a warp roll, elevating means on top of the framework for raising and lowering the roll, and means for automatically stopping the elevating means when the roll has reached certain predetermined upper and lower positions.
4. In a drawing in frame having harness support means, a take-up roll, means for receiving a warp roll into the entering frame, means for elevating and lowering the warp roll and holding 40 the roll in elevated position while the drawing in operation is completed, means for automatically stopping the elevating operation of the warp roll when a predetermined height of the warp roll has been reached, and means for stopping the lowering operation of the warp roll when a predetermined degree of lowness has been reached in the lowering means.
5. In drawing in frame, a framework, means for supporting a plurality of harness members in 50 said framework, means for receiving a warp roll, means for elevating the warp roll, means for stopping the elevating means when the warp roll has reached a predetermined height, and safety means for preventing the falling of the elevating means when a portion of the elevating means is broken.
6. In drawing in frame having means for receiving a warp roll, means for elevating the warp roll, means for stopping the elevating means when 60 the warp roll has reached a predetermined height, and swingable means for at least partially supporting the warp roll.
7. In drawing in frame having a framework, approximately vertically disposed side posts to 65 said framework, guideways in said posts, elevating means slidably mounted in said guideways, a cable secured to each of the elevating means, said elevating means being adapted to receive a warp roll while in lowered position, means on top of 70 the frame for winding the cables onto suitable drums for raising the warp roll, motor driven

means for imparting movement to said drums, means for automatically stopping the motor driven means when the warp roll has reached a predetermined height.

8. A drawing in frame comprising a frame portion having the usual harness frames therein, vertically disposed guideways in said frame portion, laterally extending arms from said guideways, one of said arms being pivoted, said arms being adapted to receive a warp roll while in lowered position, elevating and lowering means for said arms and warp roll comprising a cable secured to the sliding means in each of the said uprights, a transversely disposed member having drums thereon to which the upper end of each of the cables are secured, a motor for driving said transversely disposed means, means for automatically stopping the motor when the arms and the sliding means with the warp roll thereon have reached a predetermined height, and means for automatically stopping the motor when the elevating and lowering means have been lowered to a predetermined position.

9. A drawing in frame for textiles comprising vertically disposed standards having a cross piece secured to the upper end thereof, guideways in said vertically disposed members, sliding members mounted in said guideways, laterally projecting arms extending from said sliding means, one of said arms having a pivot intermediate its ends permitting lateral movement of the outer end of the arm, said arms having bearing portions in their outer ends for the reception of a warp roll, means for simultaneously elevating the said arms comprising cables having their lower ends secured to said sliding means, a transversely disposed member at the upper end of the framework and having drums thereon to which said cables are secured, means for imparting rotation to said transversely disposed member, means for automatically stopping said elevating means when the elevating means and the sliding means supporting the same have been raised to a predetermined position of elevation and means for automatically stopping the warp roll when the warp roll has been lowered to a predetermined position.

10. A drawing in frame comprising a framework and the usual harness supporting means, warp roll receiving means, means for elevating the warp roll to the upper portion of the frame comprising a motor, means for automatically stopping the motor when the warp roll has been raised to a predetermined position and means for reversing the direction of rotation of the motor to lower the warp roll and means for stopping the motor when the warp roll has been lowered to a predetermined position.

11. A drawing in frame having a framework with vertically slideable members mounted therein for the reception of a warp roll, a portion of one of said members being movable laterally with relation to each other for the reception of the warp roll, motor driven means for elevating the warp roll, means for arresting the elevating operation, means for reversing the direction of rotation of the motor and means for automatically stopping the motor when the warp roll has been lowered to a predetermined position.

JOHN G. BENTLEY.

ROBERT A. GIBBS, JR.
